US00D936198S

(12) **United States Design Patent** (10) **Patent No.:** **US D936,198 S**
Eide (45) **Date of Patent:** **** Nov. 16, 2021**

(54) **OZONE PLATE FOR AN AIR PURIFICATION DEVICE**

(71) Applicant: **DBG GROUP INVESTMENTS, LLC**,
Dallas, TX (US)

(72) Inventor: **Andrew Eide**, Rockwall, TX (US)

(73) Assignee: **DBG GROUP INVESTMENTS, LLC**,
Dallas, TX (US)

(**) Term: **15 Years**

(21) Appl. No.: **29/721,679**

(22) Filed: **Jan. 22, 2020**

(51) LOC (13) Cl. **23-04**

(52) U.S. Cl.

USPC **D23/363**

(57) **CLAIM**

The ozone plate for an air purification device, as shown and described.

DESCRIPTION

FIG. 1 illustrates a perspective view of an ozone plate showing the new design;

FIG. 2 illustrates a front elevation view thereof;

FIG. 3 illustrates a rear elevation view thereof;

FIG. 4 illustrates a top plan view thereof;

FIG. 5 illustrates a bottom plan view thereof;

FIG. 6 illustrates a right side elevation view thereof; and,

FIG. 7 illustrates a left side elevation view thereof.

1 Claim, 3 Drawing Sheets
